UNITED STATES PATENT OFFICE

ALBERT F. BREITENSTEIN, OF NEW HAVEN, CONNECTICUT, ASSIGNOR TO THE
GEOMETRIC TOOL COMPANY, OF NEW HAVEN, CONNECTICUT, A CORPORATION

SELF-OPENING DIE HEAD

Application filed September 9, 1931. Serial No. 561,895.

This invention relates to an improvement in self-opening die-heads and particularly to that class of self-opening die-heads commonly referred to as "inside-trip" die-heads, 5 that is to say, die-heads constructed with capacity for being automatically tripped or released from the work by the engagement of the latter with a feature within the die-head structure.

One of the main objects of my present invention is to provide an inside-trip die-head in which the inside-trip device is connected to the latching-member in such manner as to release the same with a minimum of lost 15 motion and thus provide a self-opening die-head structure of the inside-trip type which can be relied upon for accurate and sensitive action.

Another object of my invention is to provide a simple, reliable and convenient self-opening die-head having means for automatically locking its adjustable inside-trip device.

With the above and other objects in view 25 as will appear from the following, my invention consists in a self-opening die-head of the inside-trip type having certain features of construction and combinations and arrangements of parts as will be hereinafter described and particularly recited in the claims.

In the accompanying drawings:

Fig. 1 is a view in side elevation of one form which a self-opening die-head embodying my invention may assume;

Fig. 2 is a view thereof in front elevation;

Fig. 3 is a view thereof in rear end elevation;

Fig. 4 is a central longitudinal sectional view taken on the line 4-4 of Fig. 2 but on a larger scale, the parts being shown in the positions which they assume when the chasers are in their closed or cutting positions;

Fig. 5 is a central longitudinal sectional view corresponding to Fig. 4 but showing the parts in the positions which they assume when the die-head is tripped and showing, in addition, a wrench inserted in the adjustable tripping-stem for adjusting the same;

Fig. 6 is a transverse view taken on the line 6-6 of Fig. 4;

Fig. 7 is a similar view taken on the line 7-7 of Fig. 4;

Fig. 8 is a similar view taken on the line 8-8 of Fig. 4;

Fig. 9 is a broken detail view in longitudinal section taken on the line 9-9 of Fig. 6;

Fig. 10 is a similar view taken on the line 10-10 of Fig. 6;

Fig. 11 is a broken detail longitudinal sectional view taken on the line 11-11 of Fig. 2;

Fig. 12 is a view partly in side elevation and partly in longitudinal section of the internal adjustable tripping-stem;

Fig. 13 is a view looking toward the front end thereof;

Fig. 14 is a view looking toward the rear end thereof;

Fig. 15 is a perspective view of the latching-plunger detached; and

Fig. 16 is a perspective view of the tripping-slide detached.

The self-opening die-head herein chosen for the illustration of my invention consists, as shown, of a body-member 20 having a rearwardly-extending hollow shank 21 and provided at its forward end with an enlarged head-portion 22, which latter is formed in its forward face with four (more or less) equidistant radial slots 23 in each of which is mounted a radially-movable chaser 24.

The chasers 24 are retained in place in the slots 23 in the head-portion 22 of the body-member 20 by means of segmental plates 25 and are each formed at their respective outer ends with a sloping cam-surface 26 each engaged by a similarly-sloped cam-surface 27, one of which latter is formed adjacent each of the said chasers upon the inner forward corner of a cup-shaped chaser-operating sleeve 28. The said sleeve is mounted upon the body-member with capacity for axial sliding movement and bears at its forward end upon the periphery of the head-portion 22 of the said body-member and at its rear end upon the periphery of a latch-carrying ring 29 mounted upon the said body-member with capacity for axial adjustment, which adjustment is effected by an adjusting-nut 30

threaded upon the body-member just forward of the shank 21 thereof.

The latch-carrying ring 29 above referred to is formed with a transverse-notch 31 provided for the accommodation of a latch-member 32 of substantially semicircular form and provided with a central operating-tang 33 inwardly-projecting through a clearance-slot 34 formed in the body-member 20, as clearly shown in Figs. 4 and 5 of the drawings.

The outer forward corner of the latch-member 32 is adapted to engage with a substantially-semicircular eccentric latching-shoulder 35 formed in the interior of the chaser-operating sleeve 28 for the purpose of releasably holding the said sleeve in its forward chaser-closing position against the counter-urge of a pair of retracting springs 36—36 respectively located at diametrically-opposite points in the die-head structure and having their forward ends seated in sockets 37 rearwardly opening through the head-portion 22 of the body-member 20 and their rear ends seated in sockets 38 forwardly opening from the adjacent contracted portion of the chaser-operating sleeve 28.

To provide for disengaging the latching-member 32 from the latching-shoulder 35 in the chaser-operating sleeve 28 by means of an external abutment to permit the rearward retirement of the said sleeve under the urge of its springs 36—36 in order to permit the chasers 24 to move radially outward into their retired positions, I employ a tripping-sleeve 39 mounted upon the chaser-operating sleeve 28 with capacity for axial movement thereon. The said tripping-sleeve 39 is provided with an internal cam-surface 40 adapted when the sleeve is moved rearwardly to exert inward pressure upon a ball 41 which is located in a radial guide-passage 42 in the rear portion of the chaser-operating member 28 and bears upon the periphery of the latching-member 32.

As thus constructed, it will be seen that when the die-head is in use and with the parts in the positions in which they are shown in Fig. 4, a relative rearward draft upon the tripping-sleeve 39 will, through the intermediary of the ball 41, effect the inward movement of the latching-member 32 and its consequent disengagement from the latching-shoulder 35 with the effect of permitting the chaser-operating sleeve 28 to move rearwardly from the position in which it is shown in Fig. 4 to the position in which it is shown in Fig. 5.

The general organization above described may be said to be old in the art and has been set forth and described herein for the purpose of enabling the operation of my improved inside-trip feature to be properly understood.

It may be here stated that, broadly speaking, inside-trips are old in the art and I wish,

therefore, to call particular attention to the novel connection of the inside-trip device with the latch 32, or its equivalent, and the automatic locking feature of the said inside-trip device, as will be presently described.

The body-member 20 is formed with an axially-arranged cylindrical chamber 43, the rear end of which is reduced in diameter as at 44 and extends throughout the length of the shank 21 of the said body-member. Mounted in the enlarged forward end of the chamber 43 is the cylindrical-contoured head-portion 45 of what I shall, for convenience of description, refer to as a tripping-slide 46 having also a rearwardly-extending hollow shank 47 sliding in the reduced portion 44 of the axial bore in the shank 21 of the body-member 20.

The tripping-slide 46 above referred to is mounted within the body-member as above described with capacity for axial movement and is provided with a rearwardly-and-outwardly-inclined passage 48 receiving the similarly-sloped operating-tang 33 of the latching-member 32 already described. The tripping-slide 46 is normally held at the limit of its forward movement by means of a spring 49 encircling its shank 47 and bearing at its forward end against the head-portion 45 and at its rear end against a shoulder 50 formed at the junction of the chamber 43 proper with its reduced rear-extension 44, as clearly shown in Figs. 4 and 5.

The tripping-slide 46 has extending therethrough an axial bore 51 formed at its forward end with internal threads for engagement with an externally-threaded adjustable tripping-stem 52 also provided, in turn, with an axial bore 53, which latter at the forward end of the stem is enlarged as at 54 and shaped into hexagonal form in cross-section for the reception of the similarly-shaped terminal 55 of a wrench 56 by means of which the said stem may be screwed inwardly or outwardly in the tripping-slide 46 as may be desired. The rear end of the tripping-stem 52 is formed with two diametrical grooves 57—57 which intersect each other at a right angle and result in the formation of four latching-abutments or bosses 57^a, as clearly shown in Fig. 13 of the drawings.

Mounted within the bore 51 of the tripping-slide 46 just to the rear of the tripping-stem 52 is a spring-pressed latching-plunger 58 having capacity for axial sliding movement and provided with a forwardly-extending stem 59 reciprocating in the bore 53 of the tripping-stem 52 and normally having its forward end projecting into the hexagonal forward end 54 thereof. At the junction-point of its stem 59 the latching-plunger 58 is provided with a forwardly-projecting diametrical rib 60 adapted to enter either one of the two diametrical grooves 57—57 formed

in the rear face of the tripping-stem 52, as before described.

To normally maintain the rib 60 of the latching-plunger 58 in either one of the diametrical grooves 57—57 in the tripping-stem 52, I employ a spring 61 housed within the rear portion of the bore 51 in the said tripping-slide and bearing at its forward end against the rear face of the latching-plunger 58 and at its rear end against the forward face of a plug 62 threaded into the rear end of the shank 47 of the said tripping-slide.

To provide for coupling the latching-plunger 58 to the tripping-slide 46 against relative rotary movement but with capacity for relative axial movement I install in the said latching-plunger a diametrical key 63 projecting at its respective opposite ends into longitudinal slots 64—64 formed in the wall 20 of the shank 47 of the said tripping-slide at diametrically-opposite points therein. The key 63 just referred to is retained in place by means of a set-screw 65 threaded into a boss 66 rearwardly-projecting from the latching-plunger 58 and serving as a centering-guide for the forward end of the spring 61.

To prevent the tripping-slide 46 from rotating within the body-member 20, I provide the latter with an inwardly-projecting T-shaped key 67 having its cylindrical stem 68 seated in the radial bore 69 in the said body-member and having its head-portion entered into a longitudinal keyway 70 formed in the periphery of the head-portion 45 of the said tripping-slide 46.

The inside-trip feature of my improved self-opening die-head operates in the following manner;

Let it be supposed that the parts are in the positions in which they are shown in Fig. 4 and that the die-head is threaded over the work, or the work threaded into the die-head, so that the work ultimately abuts against the forward face of the tripping-stem 52 with the effect of moving the same relatively rearwardly, together with the tripping-slide 46, of which it forms an adjustable extension.

The rearward movement of the tripping-stem 52 and tripping-slide 46 as just above described will cause the forward wall of the inclined-passage 48 of the latter to act with a cam-like action upon the forward face of the tang 33 with the effect of forcibly pulling the latching-member 32 inwardly to disengage its forward outer corner from the latching-abutment 35 within the chaser-operating sleeve 28 and thus permit the latter to move rearwardly for effecting the retraction of the chasers 24 under the urge of the retracting-springs 36—36. The parts will now have assumed the positions in which they are shown in Fig. 5.

What I wish, in particular, to call attention to in the tripping action above described

is the direct coaction of the tripping-slide with the latching-member 32 for effecting the retraction thereof and thus the opening of the die-head. This direct connection results in obviating one of the main objections heretofore possessed by prior types of inside-trip die-heads for the reason that it so minimizes lost motion as to make the inside-trip feature so accurate and sensitive as to be equivalent in these two essential properties to outside-trip mechanisms.

The particular die-head herewith chosen for the illustration of my invention is also capable of being tripped by means of a relatively-rearward thrust exerted upon the tripping-sleeve 39, as has been hereinbefore described.

Now let it be supposed that it is desired to cut a longer thread upon a piece of work than the tool is set for in the accompanying drawings before the latch 32 is retracted to effect the retirement of the chasers and hence the cessation of the threading operation. This adjustment may be effected by inserting the polygonal terminal 55 of a wrench such as 56 into the hexagonal socket 54 in the forward end of the tripping-stem 52.

The insertion of the wrench in the manner above described and as shown in Fig. 5 will effect the rearward movement of the latching-plunger 58 to a degree sufficient to disengage its coupling-rib 60 from whichever of the grooves 57—57 in which it may have been located, so that the said tripping-stem 52 may now be rotated by means of the wrench 56 as required to effect the desired adjustment of the tripping-point of the die-head.

When the tripping-stem 52 has been adjusted to the desired point, the withdrawal of the wrench 56 will permit the spring 61 to move the latching-plunger 58 forwardly again so as to reengage its coupling-rib 60 with whichever one of the grooves 57—57 in the tripping-slide at that time happens to be aligned with it, so that the said tripping-stem is locked in its newly-adjusted position against accidental displacement.

It will be understood by those skilled in the art that my invention may assume varied physical forms without departing from my inventive concept and I, therefore, do not limit myself to the specific embodiment herein chosen for illustration; but only as indicated in the appended claims.

I claim:

1. In a self-opening die-head, the combination with the body, chasers, and chaser-operating member thereof; of a radially and axially movable latching-member adapted to releasably hold the said chaser-operating member in its chaser-closing position; a tripping-member mounted within the die-head structure in position to be moved by engagement with the work and engaged directly with a portion of the said latching-member

for moving the same radially inward into its unlatched position, and adjusting-means for moving the said latching-member axially for the adjustment of the chasers.

6. 2. In a self-opening die-head, the combination with the body, chasers, and chaser-operating member thereof; of a latching-member adapted to releasably hold the said chaser-operating member in its chaser-closing

10 position and provided with an inwardly-extending tang having an inclined cam-surface; and a tripping-member mounted within the die-head structure in position to be moved by engagement with the work and

15 provided with a cam-surface engaging directly with the cam-surface upon the tang of the said latching-member, the slope of the two said cam-surfaces being such that a relative rearward thrust upon the said tripping-member will effect the retraction of the said latching-member.

3. In a self-opening die-head, the combination with the body, chasers, and chaser-operating member thereof; of a latching-

25 member adapted to releasably hold the said chaser-operating member in its chaser-closing position; and a two-part tripping-member located within the die-head structure and including a tripping-slide engaged directly

30 with a portion of the said latching-member itself for releasing the same, and a stem adjustably connected with the said tripping-slide and located in position to be engaged with the work.

35 4. In a self-opening die-head, the combination with the body, chasers, and chaser-operating member thereof; of a latching-member adapted to releasably hold the said chaser-operating member in its chaser-closing

40 position and provided with an inwardly-extending tang having an inclined cam-surface; and a two-part tripping-member located within the die-head structure and including a tripping-slide provided with a

45 cam-surface engaging directly with the cam-surface upon the tang of the said latching-member, and a stem adjustably connected with the said tripping-slide and located in position to be engaged with the work, the

50 slope of the two said cam-surfaces being such that a relative rearward thrust upon the said two-part tripping-member will effect the retraction of the said latching-member.

55 5. In a self-opening die-head, the combination with the body and chasers thereof; of a chaser-latching member; a two-part releasing-device for the said chaser-latching member, mounted within the die-head structure and including an inner-member and an outer-

60 member screw-threaded together for relative adjustment and mounted within the die-head structure in position to have the said outer-member engaged by the work and the said inner-member operatively connected to the

65 said chaser-latching member for releasing the

same, the said outer-member having a wrench-engaging portion; and a latching-member releasably interlocking the inner- and outer-members of the said releasing-device and having a portion located adjacent the wrench-engaging portion of the said outer-member in position to be engaged by a wrench for being moved thereby to effect the unlatching of the said outer-member from the said inner-member as an incident to the engagement of the said wrench with the said outer-member.

6. In a self-opening die-head, the combination with the body and chasers thereof; of a chaser-latching member; a two-part releasing-device mounted within the die-head structure and operatively connected to the said chaser-latching member, and including a slide and a slide-extension screw-threaded to the said slide and having a wrench-en-

70 gaging portion; and a latching-member releasably interlocking the said slide and the said slide-extension and having a portion located adjacent the wrench-engaging portion of the said slide-extension in position to be

75 engaged by a wrench for being moved thereby to effect the unlatching of the said slide and slide-extension as an incident to the engagement of the said wrench with the said

80 slide-extension.

7. In a self-opening die-head, the combination with the body and chasers thereof; of a chaser-latching member; a two-part releasing-device mounted within the die-head struc-

90 ture, operatively connected to the said chaser-latching member, and including a slide and a slide-extension screw-threaded to the said slide and having a wrench-receiving socket; and a latching-member releasably interlock-

95 ing the said slide and the said slide-extension and having a portion located in the wrench-receiving socket of the said slide-extension in position to be engaged by a wrench for being moved thereby to effect the unlatching of the

100 said slide and slide-extension as an incident to the insertion of a wrench into the socket of the said slide-extension.

8. In a self-opening die-head, the combination with the body and chasers thereof; of a chaser-latching member; a two-part releas-

105 sing-device mounted within the die-head structure and operatively connected to the said chaser-latching member, and including a slide and a hollow slide-extension screw-

110 threaded to the said slide and having a wrench-engaging portion; and a latching-member releasably interlocking the said slide and the said slide-extension and having a

115 stem forwardly projecting through the said hollow slide-extension into a position adja-

120 cent the wrench-engaging portion of the latter so as to be moved by a wrench to effect the unlatching of the said slide and slide-ex-
125 tension as an incident to the engagement of

the said wrench with the said slide-extension.

9. In a self-opening die-head, the combination with the body and chasers thereof; of a chaser-latching member; a two-part releasing-device mounted within the die-head structure and operatively connected to the said chaser-latching member, and including a slide and a hollow slide-extension screw-threaded to the said slide and having a wrench-receiving socket; and a latching-member releasably interlocking the said slide and the said slide-extension and having a stem forwardly projecting through the latter into the wrench-receiving socket thereof in position to be engaged and moved by a wrench as an incident to the insertion thereof into the socket of the said slide-extension.

10. In a self-opening die-head, the combination with the body and chasers thereof; of a chaser-latching member; a two-part releasing-device mounted within the die-head structure and operatively connected to the said chaser-latching member, and including a hollow slide and a hollow slide-extension screw-threaded to the said slide and having a wrench-engaging portion; and a latching-member axially movable within the said hollow slide and having a stem forwardly projecting through the said hollow slide-extension into a position adjacent the wrench-engaging portion of the latter so as to be moved by a wrench to effect the unlatching of the said slide and slide-extension as an incident to the engagement of the said wrench with the said slide-extension.

11. In a self-opening die-head, the combination with the body and chasers thereof; of a chaser-latching member; a two-part releasing-device mounted within the die-head structure and operatively connected to the said chaser-latching member, and including a hollow slide and a hollow slide-extension screw-threaded to the said slide and having a wrench-engaging portion; a latching-member axially movable within the said hollow slide and having a stem forwardly projecting through the said hollow slide-extension into a position adjacent the wrench-engaging portion of the latter so as to be moved by a wrench to effect the unlatching of the said slide and slide-extension as an incident to the engagement of the said wrench with the said slide-extension; and a spring housed within the said hollow slide in position to exert a constant effort to force the said latching-member forward into its latching position.

12. In a self-opening die-head, the combination with the body and chasers thereof; of a chaser-latching member; a two-part releasing-device mounted within the die-head structure and operatively connected to the said chaser-latching member, and including a hollow slide and a hollow slide-extension

screw-threaded to the said slide and having a wrench-receiving socket; and a latching-member axially movable within the said hollow slide and having a stem forwardly projecting through the said hollow slide-extension into the wrench-receiving socket thereof in position to be engaged and moved by a wrench as an incident to the insertion thereof into the socket of the said slide-extension.

13. In a self-opening die-head, the combination with the body and chasers thereof; of a chaser-latching member; a two-part releasing-device mounted within the die-head structure and operatively connected to the said chaser-latching member, and including a slide and a hollow slide-extension screw-threaded to the said slide and having a wrench-engaging portion at its forward end and a latching-abutment at its rear end; and a latching-member interlocked with the said slide against relative rotary movement but free for reciprocating movement and having a latching-abutment engageable with the latching-abutment of the said slide-extension for releasably interlocking the same with the said slide and also having a stem forwardly-projecting through the said hollow slide-extension into a position adjacent the wrench-engaging portion of the latter so as to be moved by a wrench to effect the unlatching of the said slide and slide-extension as an incident to the engagement of the said wrench with the said slide-extension.

14. In a self-opening die-head, the combination with the body and chasers thereof; of a chaser-latching member; a two-part releasing-device mounted within the die-head structure and operatively connected to the said chaser-latching member, and including a hollow slide and a hollow slide-extension screw-threaded to the said slide and having a wrench-engaging portion and a latching-abutment at its rear end; and a latching-member axially movable within the said hollow slide with which it is interlocked against relative rotary movement and having a latching-abutment engageable with the latching-abutment of the said slide-extension for releasably interlocking the same with the said slide and also having a stem forwardly-projecting through the said hollow slide-extension into a position adjacent the wrench-engaging portion of the latter so as to be moved by a wrench to effect the unlatching of the said slide and slide-extension as an incident to the engagement of the said wrench with the said slide-extension.

15. In a self-opening die-head, the combination with the body, chasers and chaser-operating member thereof, of a latch-carrying ring mounted upon the said body with capacity for axial adjustment thereupon, a radially and axially movable latching-member carried by the said ring, with respect to

which it has radial movement and adapted to releasably hold the chaser-operating member in its chaser-closing position, a tripping-member mounted within the die-head structure in position to be moved by engagement with the work and itself engaged directly with a portion of the latching-member for moving the same radially inward into its unlatched position, and adjusting-means for moving the said latch-carrying ring axially for adjusting the chaser-operating member.

In testimony whereof, I have signed this specification.
